Primary Examiner — Deanna L Pratt(74) *Attorney, Agent, or Firm* — Bereskin & Parr
LLP/S.E.N.C.R.L., s.r.l.(57) **CLAIM**

The ornamental design for a towable table and chairs assembly, as shown and described.

DESCRIPTION

FIG. 1 is a perspective view of a towable table and chairs assembly, shown in an open and deployed configuration;

FIG. 2 is a front view thereof;

FIG. 3 is a back view thereof;

FIG. 4 is a first side view thereof;

FIG. 5 is a second side view thereof;

FIG. 6 is a top view thereof;

FIG. 7 is a bottom view thereof;

FIG. 8 is a top view of the towable table and chairs assembly, shown with a portion being moved towards a closed configuration;

FIG. 9 is a side view of the towable table and chairs assembly, shown in a closed and deployed configuration; and,

FIG. 10 is a side view of the towable table and chairs assembly, shown in a closed and stowed configuration.

The dot-dash broken lines in FIG. 10 illustrate a vehicle towing the towable table and chairs assembly and do not form part of the claimed design.
